PROCESS AND APPARATUS FOR THE PRODUCTION OF SOUNDS OF ANY DESIRED TONE COLOR

Heinrich Konemann, Munster, Germany

Application August 31, 1931, Serial No. 560,475,
and in Germany August 30, 1930

6 Claims. (Cl. 84—1)

This invention relates to improvements in musical instruments and more particularly concerns an instrument in which a tone of any desired color or timbre may be produced.

5 It is well known that the tone color or timbre of a particular musical instrument depends upon the ratios of the amplitudes of the fundamental and overtones. Thus with a flute, for example, the amplitude of the fundamental may be fifty 10 or more times greater than the amplitude of one of the overtones. It has been difficult heretofore to produce synthetically, say, by means of lip pipes, a mixture of the fundamental and overtones in which the proper ratio of amplitudes of 15 the several tones is present. On the one hand if the fundamental is produced at the proper amplitude, then no sound is produced when the overtone pipes are blown at such a reduced amplitude that the amplitude of the overtone is but one 20 50th part of the amplitude of the fundamental tone. If on the contrary, the overtones are produced with the desired amplitudes, and it is sought to produce a fundamental with an amplitude fifty times as great as the latter, the pipe of 25 the fundamental is "overblown", i. e., it no longer gives a pure sinusoidal vibration and the final mixture does not have the desired tone color. The same is true of other instruments.

According to the present invention, the individual acoustic vibrations are produced at a suitable amplitude for the lip pipes or other devices which are commonly employed in producing these tones. Each device is so tuned to give its particular pitch, and these pitches are so arranged with 35 respect to one another as to provide the fundamental and the desired overtones for a succession of tones in the chromatic or other scale at their most suitable amplitudes for mechanical production of tones. The acoustic vibrations are then 40 converted into electrical oscillations and in this condition brought by resistances being inserted to an amplitude suited for the tone color desired, and are mixed to produce a complex of electrical oscillations, which after amplification 45 to the desired degree, are re-converted into acoustic vibrations of the desired strength.

The invention, however, although illustratively described hereinafter as employed with lip pipes, is not so limited, as other tone producing devices 50 such as tuning forks, reeds, or the like may be employed for producing electric currents of the prescribed frequencies.

In the drawings is set forth one example of 55 execution of a musical instrument according to this invention in which lip pipes are employed for the production of the sounds of a tone color desired.

In these drawings:

60 Fig. 1 diagrammatically shows the arrange-

ment of the pipes and their keyboard in perspective.

Fig. 2 the same in a diagrammatic plan.

Fig. 3 a vertical sectional view showing the connections of a key with pipes, and the device 65 for converting the acoustic vibrations into electrical oscillations.

Fig. 4 diagrammatically the arrangement of the electrical parts of the instrument.

The instrument comprises a plurality of lip or 70 organ pipes arranged in series such that each series has a pipe delivering the fundamental, and other pipes delivering the desired overtones corresponding to this fundamental. When the corresponding key is depressed, all the pipes of 75 this series are blown. In the drawings, the instrument is illustrated as being provided with pipes in each series for delivering the fundamental and the first four overtones. Each series corresponds to one step in the chromatic scale, for 80 example. Thus when the key a_1 is depressed (Figs. 2 and 4), the pipes b_1^0 , b_1^1 , b_1^2 , b_1^3 and b_1^4 are sounded. Similarly, when the key a_2 is depressed, the pipes b_2^0 , b_2^1 , b_2^2 , b_2^3 and b_2^4 are sounded and similarly for the remaining keys 85 and pipes. It will be understood that although devices for producing only the first four overtones are shown, any desired number of such overtone device may be provided.

Since each of the series is preferably identical 90 in construction, save for the size of the pipes therein, an illustrative form of construction for one key and the corresponding pipes is shown in Fig. 3, in which the key a is illustrated as depressed whereby its crank arm 10 has drawn the link 11 to the left and worked the crank 12 to open the valve 13 leading from the wind chest 14 into the pipe B^0 , so that this pipe sounds with the fundamental tone corresponding to the key a . At the same time, the movement of the key has raised the rod 15 and rocked the lever 16 whereby to withdraw the damper 17 from the diaphragm C and the latter sounds in resonance with the air column in the pipe B^0 , for which purpose it is made of a suitable thickness and material with 95 respect to its diameter in well known manner. A cap 18 is arranged on the pipe B , in which is supported a permanent magnet d having a winding E thereon connected to the electrical leads 19. For clearness of the drawings, this cap is illustrated on top of the lip pipe, although obviously this is not essential to the invention so long as a sufficient movement of the responding element such as the diaphragm C. It is preferred to provide an adjustable stop K in each pipe to restrict the cross section through which the air column in the pipe B^0 operates upon the diaphragm C. 105

The link 11 also leads to a crank lever 20 which in turn is connected to a link 15a to a lever 16a 110 operating in a second pipe B^1 . The wind chest 115 120

14a likewise contains a valve 13a operated by the link 11 so that the second pipe B¹ is also sounded when the key a is depressed. The cap 18a of this pipe B¹ likewise contains an electromagnet and 5 the diaphragm and stop arrangement is provided as with the pipe B⁰, so that upon the sounding of the pipe B¹, an electrical oscillatory current passes in the external leads 19a and is of the frequency of pipe B¹.

10 The same construction is employed for each of the other pipes in each of the other pipes in each series, so that upon depression of a given key A, the fundamental and overtones are sounded which correspond thereto, and sinusoidal alternating currents are produced in the corresponding external leads. Further, each of the series is similarly constructed. All of the external leads of the fundamental pipes b¹, b⁰, b³ . . . b¹⁰ (Fig. 2) are connected in parallel 15 (Fig. 4). Similarly, all of the external leads for the first, second, third and fourth overtones are connected in parallel. Hence, as shown in Fig. 20 4, the coils e₁⁰, e₂⁰, e₃⁰, e₄⁰ . . . e₁₀⁰, are connected to the input winding of a transformer f, which has 25 a corresponding secondary winding 30 connected to a potentiometer resistance g. A tap connection 31 on this resistance is connected through a condenser 32 with a bus wire 33 which is connected to an input condenser 34 with the grid of 30 an input amplifying tube h, which is provided, for example, with the usual input resistance W and has cathode energizing batteries 35 and the anode or spaced current battery 36. A second stage h^a is connected in cascade, and further 35 amplifies the current and delivers it to a loud speaker i. A variable resistance 37 is connected in shunt of the input resistance of the first tube h, and may be operated by a control handle 38 preferably located adjacent the keyboard, where- 40 by to vary the volume of the sound mixture composed of fundamentals and overtones to be delivered from the loud speaker i. Also, it is preferred to provide a handle 39 adjacent the keyboard for controlling the tap connection 31 on 45 the potentiometer resistance g⁰ by which the amplitude of the current received from the pipe devices corresponding to the fundamental tones may be regulated.

Similarly, the respective overtones have their 50 coils e₁¹, e₂¹, e₃¹ . . . parallel and are in series to the input winding f¹ of a transformer having an output winding 30a connected to a potentiometer resistance g¹ with the variable tap connection 31a controllable by a handle 39a adjacent the 55 keyboard, and connected through a condenser 32a to the common bus wire 35.

Similarly, the coils for each of the other overtones are connected in multiple and through 60 transformers and potentiometer resistances, de- 55 liver their currents respectively to the amplifier tube h₂. By suitable variation of the control handles 39, 39a, 39b, 39c, it is possible to determine the amplitudes of the fundamental or of the overtones to imitate any given instrument or 65 group of instruments and likewise to obtain any desired tone color.

In order that the alternating current potentials generated in any coil E shall not pass for too great an extent through the other coils in parallel 70 thereto, but will pass through the proper transformer, the resistance of the individual coils is preferably high with respect to the resistance of the transformer itself.

The pipes are each constructed in the manner 75 well known to those skilled in the organ building

art, to give their own fundamental tones only, while permitting the overtones to sound not at all or only very weakly for each of the pipes.

If special purity is desired, and the pipe does not render its fundamental tone with sufficient freedom from overtones the space between the stop K and the diaphragm may be dimensioned as a resonator responding to the fundamental tone.

It will be noted that the dampers 17, which rest against the corresponding diaphragm C when the keys a are in the upper or non-depressed position, prevent any substantial movement of the respective diaphragms C. Hence, when any key is depressed, the first overtone or octave vibration, etc., which may occur will not operate through the corresponding octave pipe etc., to produce a vibration of the diaphragm of this octave pipe etc., and thus lead to movements of the air column in this pipe, and hence by resonance cause an undesired amplitude of this first overtone, nor produce any vibration of other pipes which might lead to beat notes. By this construction, only the diaphragms are permitted to move which are released by their respective dampers upon the depression of the respective keys.

The manual controls 39, 39a . . . may be comprised in a mixing or playing board, to form a tone color keyboard so that the tone color may 105 be changed not only occasionally during a piece of music as can today be accomplished by the playing of different musical instruments flute, violin, horn etc. at proper times, but also during the same chord, the change of tone color may be 110 made. In other words, playing may be done not only by selecting the fundamental pipes and overtones to form chords, but also the tone color may be changed in a similar manner and at the same time. The tone strength is controlled by the 115 handle 38, or by other adjustment of the amplifying system in known manner.

The tone colour or timbre keyboard may be constructed in a manner differing from that indicated in Figure 1 by the handles 39, 39a . . . , 120 for example, as in the construction shown in Figures 5 to 7 or in that shown in Figures 8 to 10, and is then preferably arranged adjacent the keyboard a¹—a¹⁰ instead of above it.

Preferably, the tone color or timbre keyboard 125 is arranged not directly above the keyboard a¹ to a¹⁰ (Figure 1) but on, say, the right hand side of the instrument as will be seen in Figure 1, so that the two players, one of whom plays on the keyboard a¹ to a¹⁰, while the other plays on the 130 timbre keyboard 38 and 39 to 39c, will not disturb one another.

Preferably, the organ or lip pipes of Fig. 1 are enclosed by a housing 100 shown in dotted lines in Fig. 1 to prevent the sounds from conflicting with the sounds produced by the loud speaker i, in the event that the keyboard and the loud speaker are located close to one another.

It is obvious that the invention is not limited to the form of construction shown, but that many 140 changes may be made therein with respect to the means of generating the vibrations of individual pitch, and in the means of selecting the amplitudes of fundamental and overtones which are to be mixed, and all without departing from 145 the scope of the invention.

What I claim is:

1. Method of producing sounds of any desired tone-color, which comprises individually producing acoustic vibrations which are the funda- 150

- mentals and overtones of a plurality of different pitches, causing said vibrations independently to produce resonance in individual air columns at the fundamental frequency of each thereof 5 whereby to purify the vibrations individually, converting the purified acoustic vibrations individually into electrical oscillatory currents, controlling the amplitudes of the oscillatory currents with respect to one another to obtain a predetermined ratio of amplitudes of a fundamental and its overtones with respect to one another, mixing the currents, and reproducing acoustic vibrations from the mixed currents. 10
2. Apparatus for producing sounds of any desired tone-color, comprising pluralities of means for producing acoustic vibrations of different pitches which in each plurality include individual devices for producing the fundamental and overtones of a particular pitch and means for individually purifying said vibrations by acoustic resonance and individual converting means operated by the purified vibrations of each purifying means for converting the same into electrical oscillations, means for simultaneously operating the devices in each plurality, means common to all the fundamental, to all the first, to all the second and to all of each group of other overtone converting means for combining the electric currents of said oscillations whereby to produce individual combined electric currents each comprising the fundamental, first, second or other overtone corresponding to all the vibration producing means being operated, means for controlling the amplitudes of said individual electric currents, means for mixing all the said controlled currents to produce a mixed current, and a sound reproducing device actuated by said mixed current. 15
3. Apparatus for producing sounds of any desired tone-color, comprising pluralities of means for producing acoustic vibrations of different pitches which in each plurality include individual devices for producing the fundamental and overtones of a particular pitch and means for individually purifying said vibrations by acoustic resonance and individual converting means operated by the purified vibrations of each purifying means for converting the same into electrical oscillations, a keyboard including keys 20 which each simultaneously operate the devices in each plurality, means common to all the fundamental, to all the first, to all the second and to all of each group of other overtone converting means for combining the electric currents of said oscillations whereby to produce individual combined electric currents each comprising the fundamental, first, second or other overtone corresponding to all the vibration producing means being operated, means connected to each said common means for independently controlling the amplitudes of said individual electric currents, means for mixing all the said controlled currents to produce a mixed current, a sound reproducing device actuated by said mixed current, and a sound-proof housing enclosing all said lip pipes for preventing the interference of sounds coming directly from the lip pipes with sounds coming from the said reproducing device. 25
4. Apparatus for producing sounds of any desired tone-color, comprising pluralities of devices each including a lip pipe and a diaphragm vibrated by the air column in the pipe whereby to produce acoustic vibrations of different pitches which in each plurality include individual devices for producing the fundamental and overtones of a particular pitch and a vibration dampener for said diaphragm, means for simultaneously operating the devices in each plurality and including means for moving the dampener away from the diaphragm for each selected pipe while leaving the dampeners of non-selected pipes in contact with the diaphragms whereby to prevent interference and beating by acoustic and electrical resonance, individual converting means connected to each device for converting the acoustic vibrations into electrical oscillations, means common to all the fundamental, to all the first, to all the second and to all of each group of other overtone converting means for combining the electric currents of said oscillations whereby to produce combined electric currents each comprising the fundamental, first, second or other overtone of all the vibration producing means being operated, separate means connected to each said common means for independently controlling the amplitudes of said combined electric currents, means for mixing all the said controlled currents to produce a mixed current, and a sound reproducing device actuated by said mixed current. 30
5. Apparatus for producing sounds of any desired tone-color, comprising pluralities of means for producing acoustic vibrations of different pitches which in each plurality include individual lip pipes for producing the fundamental and overtones of a particular pitch, means for simultaneously operating the lip pipes in each plurality, and individual converting means connected to each lip pipe for converting the acoustic vibrations thereof into electrical oscillations, means common to all the fundamental, to all the first, to all the second and to all of each group of other overtone converting means for combining the electric currents of said oscillations whereby to produce individual combined electric currents each comprising the fundamental, first, second or other overtone corresponding to all the vibration producing means being operated, means connected to said common means for controlling the amplitudes of said individual electric currents, means for mixing all the said controlled currents to produce a mixed current, a sound reproducing device actuated by said mixed current, and a sound-proof housing enclosing all said lip pipes for preventing the interference of sounds coming directly from the lip pipes with sounds coming from the said reproducing device. 35
6. Apparatus for producing sounds of any desired tone-color, comprising pluralities of means for producing acoustic vibrations of different pitches which in each plurality include individual devices for producing the fundamental and overtones of a particular pitch, means for simultaneously operating the devices in each plurality, and individual converting means connected to each device for converting the acoustic vibrations into electric oscillations, pairs of conductors for connecting the converting means for the fundamentals, the firsts, the seconds, and each group of other overtone converting means in multiple for combining the electric currents of said oscillations whereby to produce individual combined electric currents each representing the fundamental, first, second or other overtone from all the vibration producing means being operated, individual current limiting means connected to said conductors, means for mixing all said combined and limited currents to produce a mixed current, and a sound-reproducing device actuated by said mixed current. 40
7. Apparatus for producing sounds of any desired tone-color, comprising pluralities of devices each including a lip pipe and a diaphragm vibrated by the air column in the pipe whereby to produce acoustic vibrations of different pitches which in each plurality include individual devices for producing the fundamental and overtones of a particular pitch and a vibration dampener for said diaphragm, means for simultaneously operating the devices in each plurality and including means for moving the dampener away from the diaphragm for each selected pipe while leaving the dampeners of non-selected pipes in contact with the diaphragms whereby to prevent interference and beating by acoustic and electrical resonance, individual converting means connected to each device for converting the acoustic vibrations into electrical oscillations, means common to all the fundamental, to all the first, to all the second and to all of each group of other overtone converting means for combining the electric currents of said oscillations whereby to produce combined electric currents each comprising the fundamental, first, second or other overtone of all the vibration producing means being operated, separate means connected to each said common means for independently controlling the amplitudes of said combined electric currents, means for mixing all the said controlled currents to produce a mixed current, and a sound reproducing device actuated by said mixed current. 45
